UNITED STATES PATENT OFFICE.

JEANNE B. ROGÉ, OF EVANSTON, ILLINOIS.

DESIGN FOR A JEWEL BOX OR SIMILAR ARTICLE.

Application filed July 5, 1924. Serial No. 10,070. Term of patent 3½ years.

To all whom it may concern:

Be it known that I, JEANNE B. ROGÉ, a citizen of France, residing at Evanston, in the county of Cook and State of Illinois, have invented a new, original, and ornamental Design for a Jewel Box or Similar Article, of which the following is a specification, reference being had to the accompanying drawing, forming a part thereof.

Fig. 1 is a plan view of a jewel box or similar article showing my new design; and

Fig. 2 is an end elevation of the same.

I claim:

An ornamental design for a jewel box or similar article, as shown.

JEANNE B. ROGÉ.
